Application February 15, 1946, Serial No. 647,932

20 Claims. (Cl. 250—27)

1

This invention relates to electron multiplier tube circuits, and more particularly to such circuits incorporating novel stabilizing means. The present application is a continuation-in-part of my copending application Serial No. 570,627 filed December 30, 1944, for "Logarithmic photometers."

In the above identified application, there are shown and described logarithmically responsive measuring circuits incorporating electron multiplier tubes. These circuits include feed-back arrangements wherein the potentials applied to the elements of the multiplier tube are made dependent upon the anode or output current of the tube. Specifically, the output current of the multiplier tube is applied to the control grid of an electronic amplifier tube which controls the potential drop across a potentiometer having equi-spaced taps connected to the elements of the multiplier tube.

In the circuits of said copending application, the voltages for all of the dynodes, or intermediate electrodes, of the multiplier tube and for the anode are derived from the equally spaced taps on the bleeder resistor or potentiometer connected in the output circuit of a pentode control tube having its output connected in series with the bleeder resistor and a source of potential. The bias applied to the pentode tube control grid is varied as an inverse function of the multiplier tube anode current. The result is that the voltage developed between the multiplier tube anode and the last dynode (or #9 dynode in the case of the RCA type 931 tube) is proportional to the bleeder current, as are also the other dynode and cathode voltages. Thus, when the level of illumination incident on the photo surface of the multiplier tube is low, the bleeder current will be high and the voltage between the anode and last dynode will be correspondingly high. Consequently, nearly all of the electrons emitted from the last dynode are collected by the anode, and the full current of which the multiplier tube is capable for that particular light level and applied dynode voltages will be utilized.

However, at higher levels of incident illumination on the multiplier tube, the bleeder current, and consequently the dynode voltages and the anode voltage, are all quite low. Under these circumstances, a small change in anode voltage will effect a very large change in anode current. This results in relatively unstable operation of the multiplier tube over the range of operating voltages.

2

It is among the objects of this invention to provide a stabilizing circuit for an electron multiplier tube; to provide an electron multiplier tube circuit in which the voltage between the last dynode and the anode of the multiplier tube is held at a substantially constant value, of a reasonably high magnitude; to provide a logarithmically responsive measuring circuit, including a multiplier tube and bleeder current feed-back means controlling the operating potentials of the dynodes of the multiplier tube, but in which the potential between the last dynode and the anode of the multiplier tube is substantially independent of the bleeder current; to provide such a measuring circuit including means for minimizing the effects of small changes in the grid voltage-plate current relation of an electronic tube controlling the bleeder feed-back current; to provide such a measuring circuit which is completely independent of all ordinary variations in supply line voltage; to provide such a measuring circuit in which calibration is not effected by changes in the characteristics of the electronic tube controlling the bleeder current feed-back means; and to provide such a measuring circuit having increased overall stability of performance.

These and other objects, advantages and novel features of the invention will be apparent from the following description and the accompanying drawing. In the drawing:

Fig. 1 is a graph illustrating the relation between the anode current and the anode-last dynode voltage of a multiplier tube.

Fig. 2 is a schematic wiring diagram illustrating one embodiment of the invention.

Fig. 3 is a schematic wiring diagram illustrating another embodiment of the invention.

Generally speaking, in accordance with the present invention an electrostatically focused electron multiplier tube is arranged to receive incident flux from a source of radiant energy. Potentials from a source of substantially constant potential are applied to the electrodes of the multiplier tube through a bleeder resistance. Equi-spaced taps on the bleeder resistance are connected to the cathode of the tube and to the intermediate multiplier electrodes or dynodes thereof. The voltage drop across the bleeder resistance is controlled as a function of the output current of the multiplier tube. In a logarithmically responsive circuit, the potentials are varied inversely with the output current of the multiplier tube.

According to the present invention, a constant

potential means or voltage stabilizer is connected in parallel circuit relation with the multiplier anode and the last multiplier electrode, or #9 dynode as it is frequently designated. Preferably, the current flow through the bleeder resistor is controlled by an electronic amplifier tube whose control grid is connected to the anode of the multiplier tube. The circuit arrangements are such that the negative bias applied to the amplifier tube control grid increases with an increase in the anode current of the multiplier tube. The output circuit of the amplifier tube is connected in series with the source of constant potential and the bleeder resistor. As the conductivity of the amplifier tube is a direct function of its control grid potential, the bleeder current will decrease with decreasing control grid potential and thus with increasing multiplier tube anode current. Accordingly, the potential drop across the bleeder resistor is varied inversely with the anode current of the multiplier tube.

A constant potential means, such as a gas filled voltage regulating tube or a battery, is connected between the cathode of the amplifier tube and the last dynode of the multiplier tube, and in series with the bleeder resistor. The input circuit of the amplifier tube, which thus is connected between the multiplier tube anode and the #9 dynode, is maintained at a constant potential irrespective of the anode current of the multiplier tube. When the arrangement is used as a densitometer, a current measuring meter, preferably a milliammeter, is connected across a small shunt resistor in the amplifier tube output circuit to measure the current flow in the output circuit, and thus provide, on a substantially uniformly graduated scale, direct readings of the density of a sample interposed between a source of light and the multiplier tube.

Referring to the drawing, Fig. 1 is a graph illustrating the relation between the anode current of the multiplier tube and the anode-dynode #9 voltage. Curve 10 represents the anode current as a function of the anode-dynode #9 voltage, with a constant level of illumination on the cathode of the multiplier tube and with a constant voltage applied to the remaining dynodes. In a practical example, at voltages up to approximately fifty volts, the magnitude of the anode current will depend to a considerable extent on the anode voltage. At the higher levels of illumination, the anode current varies only slightly with increasing anode-dynode #9 voltage. Thus, the bleeder resistor current, and consequently the dynode voltages and anode voltage are all quite low. A small change in anode voltage will effect a very large change of anode current. If the anode-dynode #9 voltage is maintained substantially constant, more particularly at a level above fifty volts, for instance, the bleeder resistor current will vary only slightly with changes in the anode-last dynode voltage, thus rendering the circuit more stable.

One arrangement for accomplishing this result is illustrated in Fig. 2. Referring to Fig. 2, a light source such as an incandescent lamp 15 is arranged to direct light upon the cathode 16 of a photomultiplier tube 20. Photomultiplier tube 20 may, for example, be of the RCA-931 type. Light from lamp 15 is condensed by a lens 11 and directed through a filter 12 on to a sample 13 mounted on a suitable support 14.

Photomultiplier tube 20 also includes an anode 25, nine multiplier electrodes or dynodes, of which the first eight are designated generally by the ref-

erence numeral 17 and the last, or #9 dynode, is designated as 30.

The operating potentials applied to cathode 16, anode 25, and dynodes 17 and 30 are obtained from a suitable voltage divider or bleeder resistor 35, having a relatively negative terminal 21 connected to the negative terminal 22 of a substantially constant potential source of direct current having a positive terminal 23. While the source of power has been indicated as direct current, the invention may also be practiced with alternating current. Direct current has been indicated merely for the purpose of more clearly illustrating the application of the principles of the invention.

The voltage divider comprises resistors 35 connected in series, with cathode 16 connected to the relatively negative terminal 21 of the series, anode 25 connected to the relatively positive terminal 24 of the series, through the input circuit of a pentode amplifier tube 40, and dynodes 17 each connected to a common junction of two adjacent connected resistors. Dynode 30 is connected directly to relatively positive terminal 24.

A conductor 26 connects anode 25 to the control grid 27 of tube 40. A grid biasing resistor 28 is connected from junction point 31 to the positive terminal 32 of constant potential source, such as a battery 33. Battery 33 may be, in a practical example, either a 90-volt battery or a 90-volt or 105-volt voltage stabilizer tube connected to a conventional source of potential. Screen grid 34 of pentode 40 is likewise connected to positive terminal 32, and anode 36 of the pentode is connected to the positive terminal 23 of the constant potential source.

The potential between multiplier electrode 30 (dynode #9) and anode 25 is controlled by a suitable constant potential means. In the circuit of Fig. 2, a gaseous discharge regulating tube 45 is connected between cathode 37 of pentode 40 and relatively positive terminal 24 of resistors 35, through a small resistor 38. Gaseous discharge tube 45 is preferably one in which the voltage drop therethrough is about fifty-five volts and is independent of the current flow through the tube. Thus, discharge tube 45 maintains a substantially constant potential of about fifty-five volts between anode 25 and #9 dynode 30. The common junction of tube 45 and resistor 38 is connected to one terminal of an indicating meter 50 and to the relatively negative terminal 41 of battery 33. The other terminal of meter 50 is connected to relatively positive terminal 24 of resistor series 35 and through a resistor 42 and an adjustable tap 43 to an intermediate terminal of battery 33. Meter 50 is thus shunted across resistor 38, whereby the potential drop across the resistor, which is a function of the bleeder current of resistors 35, may be measured by meter 50.

The portion of battery 33 between negative terminal 41 and tap 43, in combination with resistor 42, provides a bucking current for meter 50. The reason for this is that, on any uniform scale ammeter used in a densitometer circuit, infinite density would theoretically yield an infinite positive or negative response. For obvious reasons, only a finite range of density can be measured by the meter. Accordingly, a bucking current is introduced into the meter circuit so that the meter will read the maximum measurable density at one extreme of its scale.

The operation of the circuit is as follows. Cathode 37 is maintained at a potential approximately

55 volts positive with respect to terminal 41 of battery 33, due to voltage stabilizer tube 45. The difference in potential between the positive terminal and grid resistor 28, which latter may be approximately 100 megohms, is thus approximately 35 volts. The potential of grid 27 with respect to cathode 37 will be approximately 35 volts minus the IR drop through resistor 28 due to the anode current of multiplier tube 20. The ohmic value of resistor 28 is so related to the usual values of anode current of multiplier tube 20 that the actual grid-cathode potential of amplifier tube 40 is negative at all times in the particular case under consideration, and has a variation of only a few volts under normal operating condition.

The very high positive grid resistor terminal voltage and the high ohmic value of the grid resistor minimizes the effects of changes in the grid voltage-plate current characteristics of multiplier tube 40. For example, a change of about one-quarter volt in the control grid voltage-plate current characteristic of tube 40 would appreciably change the overall instrument calibration in the circuit described in the above identified application. However, in the present case, such a change would not be serious, as the anode current of multiplier tube 20 would change by only 0.0025 microampere to restore the amplifier tube plate-cathode current to its original value.

The density of sample 13 is an inverse logarithmic function of its transmission. The transmission is a direct measure of the light transmitted through the sample from source 15 and incident on cathode 16 of multiplier tube 20. Thus, the density of sample 13 is an inverse logarithmic function of the light incident upon cathode 16 through the sample.

As set forth in the above identified parent application, the anode current of a photomultiplier tube may be varied the proper amount to obtain a logarithmic response if the operating potentials applied to its dynodes are linearly attenuated in accordance with the anode current. This is accomplished by pentode 40 controlling the bleeder current through resistor series 35 in accordance with the anode current of multiplier tube 20. As the multiplier tube anode current increases, the potential drop across grid biasing resistor 28 increases, thus making the control grid 27 more negative with respect to cathode 37. This, in turn, increases the internal resistance of pentode 40 and thus decreases its conductivity. Therefore, the bleeder current from the constant potential source flowing through resistor series 35 is reduced in proportion to the increase in anode current of multiplier tube 20. The potentials applied between cathode 16, and dynodes 17 and 30 is thus linearly reduced in proportion to the increase in the current from anode 25.

As explained in the copending application, a meter connected to measure the output current of multiplier tube 20, in such a circuit as that described, will provide direct readings of density upon a uniformly graduated scale. Meter 50 is connected across shunt resistor 38 and thus measures the potential drop through the shunt resistor which, in turn, is a function of the current flow through bleeder resistor series 35. This current flow is, in turn, a function of the anode current of multiplier tube 20.

Gaseous discharge voltage regulating tube 45 maintains the potential between dynode 30 and anode 25 at a substantially constant value irrespective of the current flow through tube 45. Therefore, at high levels of illumination, resulting

in operatively low bleeder currents, the potential drop between anode 25 and dynode 30 is not varied disproportionately with respect to its variation at lower levels of illumination resulting in higher bleeder currents.

The anode voltage should not be so high that leakage currents and other undesired effects are introduced, nor should it be so low that tube 20 is operated on the steep portion of the anode voltage-anode current curve 10 shown in Fig. 1. With the insertion of tube 45 in the cathode-plate circuit of pentode 40, the anode 25-dynode 30 voltage is held at a sensibly constant value irrespective of the magnitude of the bleeder current through resistor series 35. Actually, the value will vary slightly due to the normal change in control grid 27-cathode 37 voltage of pentode 40 and the slight variation in voltage developed across tube 45 itself over the bleeder current range involved. The adverse effects introduced by changes in the control grid voltage-plate cathode current characteristics of pentode 40 do not affect the substantial constancy of the anode potential multiplier tube 20. The use of a grid resistor 28 of high ohmic value and a correspondingly high positive grid base voltage results in more stable operation than would otherwise be the case. For example, a small change in the control grid voltage producing a given plate current would require a large percentage change in the anode 25 current if the grid bias potential and ohmic value were low. In the present case, where these values are high, such small voltage change is a negligible fraction of the total bias voltage and the current change thus only a negligible fraction of the total anode 25 current.

Fig. 3 represents a modification of the invention in which a substantially constant potential battery is substituted for gaseous discharge tube 45. In Fig. 3, elements identical with those in Fig. 2 have been given corresponding reference characters. As shown, a substantially constant potential battery 60 is substituted for voltage stabilizer tube 45, and maintains the potential between anode 25 and dynode 30 at a substantially constant value irrespective of the anode current of tube 20. The circuit of Fig. 3 operates otherwise in the same manner as does the circuit of Fig. 2.

A third alternative, which has not been illustrated in order to maintain the drawings as simple as possible, is to make the portion of the bleeder resistor 35 connected between anode 25 and dynode 30, in the manner shown in the above identified application, have an ohmic value so high with respect to that of the rest of resistors 35 that the anode voltage will never drop to a point below about 50 volts, irrespective of the anode current, over the range of the instrument. This is a level considerably in excess of saturation of multiplier tube 20. However, the latter alternative is less desirable since there will be a very large range of anode voltages involved for a given change in bleeder current values.

The described circuits are substantially completely independent of all ordinary variations in supply line voltage. Additionally, the calibration is unaffected by changes due to the aging of tubes such as pentode 40 and gaseous discharge tube 45, or replacement of the latter. The only element affecting the calibration is the photomultiplier tube 20. Thus, the overall stability performance of the instrument is increased.

Furthermore, when the present multiplier tube 75 control circuit is incorporated in a densitometer

for measuring the density of a sample, a stable instrument, having its calibrations substantially unaffected by changes other than changes in the multiplier tube itself, is provided. Such an instrument provides direct readings of density upon a substantially uniformly graduated scale meter. While the circuit is particularly useful in such densitometers, it is not necessarily limited thereto, but is equally applicable to all types of multiplier tubes wherein the output current-anode voltage relationship varies at different rates over a given range of anode voltages.

While specific embodiments of the invention have been shown and described in detail to illustrate the application of the principles thereof, it will be understood that the invention may be otherwise embodied without departing from such principles.

What is claimed is:

1. An electronic measuring circuit comprising, in combination, an electron multiplier tube including an anode, a cathode and intermediate multiplier electrodes arranged therebetween; voltage means connected to the electrodes of said tube for impressing potentials therebetween; a source of potential; variable impedance means connected in electrical series relation with said source and said voltage means and effective to vary the potential drop across said voltage means; multiplier tube anode current responsive means connected in circuit relation with the output of said tube and with said variable impedance means and effective to vary the impedance of the latter, as a function of such anode current, to modulate such impressed potentials as a function of such anode current; and voltage stabilizing means in circuit connection with said anode and the adjacent multiplier electrode and effective to maintain the potential therebetween substantially constant irrespective of variations in such anode current.

2. An electronic measuring circuit comprising, in combination, an electron multiplier tube including an anode, a cathode and intermediate multiplier electrodes arranged therebetween; bleeder impedance means connected to the electrodes of said tube for impressing potentials therebetween; a source of potential; variable impedance means connected in electrical series relation with said source and said bleeder impedance means and effective to vary the potential drop across said bleeder impedance means; multiplier tube anode current responsive means connected in circuit relation with the output of said tube and with said variable impedance means and effective to vary the impedance of the latter, as a function of such anode current, to modulate such impressed potentials as a function of such anode current; and voltage stabilizing means in circuit connection with said anode and the adjacent multiplier electrode and effective to maintain the potential therebetween substantially constant irrespective of variations in such anode current.

3. An electronic measuring circuit comprising, in combination, an electron multiplier tube including an anode, a cathode and intermediate multiplier electrodes arranged therebetween; bleeder resistor means connected to the electrodes of said tube for impressing potentials therebetween; a source of potential; variable impedance means connected in electrical series relation with said source and said bleeder resistor means and effective to vary the potential drop across said bleeder resistor means; multiplier tube anode current responsive means connected in circuit relation with the output of said tube

and with said variable impedance means and effective to vary the impedance of the latter, as a function of such anode current, to modulate such impressed potentials as a function of such anode current.

4. An electronic measuring circuit comprising, in combination, an electron multiplier tube including an anode, a cathode and intermediate multiplier electrodes arranged therebetween; voltage means connected to the electrodes of said tube for impressing potentials therebetween; a source of potential; variable impedance means connected in electrical series relation with said source and said voltage means and effective to vary the potential drop across said voltage means; multiplier tube anode current responsive means connected in circuit relation with the output of said tube and with said variable impedance means and effective to vary the impedance of the latter, as a function of such anode current; and voltage stabilizing means in parallel circuit connection with said anode and the adjacent multiplier electrode and in series circuit relation with said variable impedance means and effective to maintain the potential between said anode and said adjacent multiplier electrode substantially constant irrespective of variations in such anode current.

5. An electronic measuring circuit comprising, in combination, an electron multiplier tube including an anode, a cathode and intermediate multiplier electrodes arranged therebetween; bleeder impedance means connected to the electrodes of said tube for impressing potentials therebetween; a source of potential; variable impedance means connected in electrical series relation with said source and said bleeder impedance means and effective to vary the potential drop across said bleeder impedance means; multiplier tube anode current responsive means connected in circuit relation with the output of said tube and with said variable impedance means and effective to vary the impedance of the latter, as a function of such anode current, to modulate such impressed potentials as a function of such anode current; and voltage stabilizing means in parallel circuit connection with said anode and the adjacent multiplier electrode and in series circuit relation with said variable impedance means and effective to maintain the potential between said anode and said adjacent multiplier electrode substantially constant irrespective of variations in such anode current.

6. An electronic measuring circuit comprising, in combination, an electron multiplier tube including an anode, a cathode and intermediate multiplier electrodes arranged therebetween; bleeder resistor means connected to the electrodes of said tube for impressing potentials therebetween; a source of potential; variable impedance means connected in electrical series relation with said source and said bleeder resistor means and effective to vary the potential drop across said bleeder resistor means; multiplier tube anode current responsive means connected in circuit relation with the output of said tube and with said variable impedance means and effective to vary the impedance of the latter, as a function of such anode current, to modulate such impressed potentials as a function of such anode

potential between said anode and said adjacent multiplier electrode substantially constant irrespective of variations in such anode current.

13. A logarithmically responsive electronic measuring circuit comprising, in combination, an electron multiplier tube including an anode, a cathode and intermediate multiplier electrodes arranged therebetween; voltage means connected to the electrodes of said tube for impressing potentials therebetween; a source of potential; variable impedance means connected in electrical series relation with said source and said voltage means and effective to vary the potential drop across said voltage means; multiplier tube anode current responsive means connected in circuit relation with the output of said tube and with said variable impedance means and effective to vary the impedance of the latter, as an inverse function of such anode current, to modulate such impressed potentials as an inverse function of such anode current; and voltage stabilizing means in circuit connection with said anode and the adjacent multiplier electrode and effective to maintain the potential therebetween substantially constant irrespective of variations in such anode current.

14. A logarithmically responsive electronic measuring circuit comprising, in combination, an electron multiplier tube including an anode, a cathode and intermediate multiplier electrodes arranged therebetween; bleeder resistor means connected to the electrodes of said tube for impressing potentials therebetween; a source of potential; a thermionic amplifier tube having its output connected in electrical series relation with said source and said bleeder resistor means and effective to vary the potential drop across said bleeder resistor means; multiplier tube anode current responsive means connected in circuit relation with the output of said multiplier tube and with the input of said amplifier tube and effective to vary the amplification factor of the latter, as an inverse function of such anode current, to modulate such impressed potentials as an inverse function of such anode current; and voltage stabilizing means in circuit connection with said anode and the adjacent multiplier electrode and effective to maintain the potential therebetween substantially constant irrespective of variations in such anode current.

15. A logarithmically responsive electronic measuring circuit comprising, in combination, an electron multiplier tube including an anode, a cathode and intermediate multiplier electrodes arranged therebetween; voltage means connected to the electrodes of said tube for impressing potentials therebetween; a source of potential; a thermionic amplifier tube having its output connected in electrical series relation with said source and said voltage means and effective to vary the potential drop across said voltage means; multiplier tube anode current responsive means, including a conductor connecting said anode to the control grid of said amplifier tube, effective to vary the amplification factor of the latter, as an inverse function of such anode current, to modulate such impressed potentials as an inverse function of such anode current; and voltage stabilizing means in parallel circuit connection with said anode and the adjacent multiplier electrode and effective to maintain the potential therebetween substantially constant irrespective of variations in such anode current.

16. A logarithmically responsive electronic measuring circuit comprising, in combination,

electron multiplier tube including an anode, a cathode and intermediate multiplier electrodes arranged therebetween; bleeder resistor means connected to the electrodes of said tube for impressing potentials therebetween; a source of potential; a thermionic amplifier tube having its output connected in electrical series relation with said source and said bleeder resistor and effective to vary the potential drop across said bleeder resistor; multiplier tube anode current responsive means, including a conductor connecting said anode to the control grid of said amplifier tube, effective to vary the amplification factor of the latter, as an inverse function of such anode current, to correspondingly vary the bleeder current to modulate such impressed potentials as an inverse function of such anode current; and voltage stabilizing means in parallel circuit connection with said anode and the adjacent multiplier electrode and effective to maintain the potential therebetween substantially constant irrespective of variations in such anode current.

17. A logarithmically responsive electronic measuring circuit comprising, in combination, an electron multiplier tube including an anode, a cathode and intermediate multiplier electrodes arranged therebetween; a bleeder resistor having one terminal connected to said cathode and the other terminal connected to the multiplier electrode adjacent said anode; circuit means connecting equi-spaced points on said resistor to the other multiplier electrodes; a thermionic amplifier tube having a cathode connected to said other resistor terminal for controlling the bleeder current through said resistor to modulate the potentials impressed on the elements of said multiplier tube; a source of potential; means connecting one terminal of said source to said one resistor terminal and the other terminal of said source to the plate of said amplifier tube; multiplier tube anode current responsive means, including a conductor connecting said anode to the control grid of said amplifier tube, effective to vary the amplification factor of the latter, as an inverse function of such anode current, to correspondingly vary the bleeder current to modulate such impressed potentials as an inverse function of such anode current; and voltage stabilizing means in circuit connection with said anode and the adjacent multiplier electrode and effective to maintain the potential therebetween substantially constant irrespective of variations in such anode current.

18. A logarithmically responsive electronic measuring circuit comprising, in combination, an electron multiplier tube including an anode, a cathode and intermediate multiplier electrodes arranged therebetween; a bleeder resistor having one terminal connected to said cathode and the other terminal connected to the multiplier electrode adjacent said anode; circuit means connecting equi-spaced points on said resistor to the other multiplier electrodes; a thermionic amplifier tube having a cathode connected to said other resistor terminal for controlling the bleeder current through said resistor to modulate the potentials impressed on the elements of said multiplier tube; a source of potential; means connecting one terminal of said source to said one resistor terminal and the other terminal of said source to the plate of said amplifier tube; a grid biasing potential source having one terminal in circuit connection with the cathode of said amplifier tube and the other terminal connected, in series with a grid biasing resistor, to the control grid of said amplifier tube; a conductor connecting said anode

to the control grid in parallel with said biasing resistor, whereby the amplification factor of said amplifier tube will be varied as an inverse function of the multiplier tube anode current to, in turn, vary the bleeder current to modulate such impressed potentials as an inverse function of such anode current; and voltage stabilizing means connected in series circuit relation with said other resistor terminal and the amplifier tube cathode to maintain the potential between said anode and such adjacent multiplier electrode substantially constant irrespective of variations in such anode current, to stabilize the operation of said circuit.

19. A logarithmically responsive electronic measuring circuit comprising, in combination, an electron multiplier tube including an anode, a cathode and intermediate multiplier electrodes arranged therebetween; a bleeder resistor having one terminal connected to said cathode and the other terminal connected to the multiplier electrode adjacent said anode; circuit means connecting equi-spaced points on said resistor to the other multiplier electrodes; a thermionic amplifier tube having a cathode connected to said other resistor terminal for controlling the bleeder current through said resistor to modulate the potentials impressed on the elements of said multiplier tube; a source of potential; means connecting one terminal of said source to said one resistor terminal and the other terminal of said source to the plate of said amplifier tube; a grid biasing potential source having one terminal in circuit connection with the cathode of said amplifier tube and the other terminal connected, in series with a grid biasing resistor, to the control grid of said amplifier tube; a conductor connecting said anode to the control grid in parallel with said biasing resistor, whereby the amplification factor of said amplifier tube will be varied as an inverse function of the multiplier tube anode current to, in turn, vary the bleeder current to modulate such impressed potentials as an inverse function of such anode current; and a gaseous discharge voltage stabilizing tube connected in series circuit relation with said other resistor terminal and the amplifier tube cathode to maintain the potential between said anode and such adjacent multiplier electrode substantially constant irrespective of variations in such anode current, to stabilize the operation of said circuit.

20. A logarithmically responsive electronic

measuring circuit comprising, in combination, an electron multiplier tube including an anode, a cathode and intermediate multiplier electrodes arranged therebetween; a bleeder resistor having one terminal connected to said cathode and the other terminal connected to the multiplier electrode adjacent said anode; circuit means connecting equi-spaced points on said resistor to the other multiplier electrodes; a thermionic amplifier tube having a cathode connected to said other resistor terminal for controlling the bleeder current through said resistor to modulate the potentials impressed on the elements of said multiplier tube; a source of potential; means connecting one terminal of said source to said one resistor terminal and the other terminal of said source to the plate of said amplifier tube; a grid biasing potential source having one terminal in circuit connection with the cathode of said amplifier tube and the other terminal connected, in series with a grid biasing resistor, to the control grid of said amplifier tube; a conductor connecting said anode to the control grid in parallel with said biasing resistor, whereby the amplification factor of said amplifier tube will be varied as an inverse function of the multiplier tube anode current to, in turn, vary the bleeder current to modulate such impressed potentials as an inverse function of such anode current; and a battery connected in series circuit relation with said other resistor terminal and the amplifier tube cathode to maintain the potential between said anode and such adjacent multiplier electrode substantially constant irrespective of variations in such anode current, to stabilize the operation of said circuit.
